Attorney.*

UNITED STATES PATENT OFFICE.

WILLIAM F. CROUCH, OF OAKLAND, CALIFORNIA.

INTERNAL-EXPLOSION ENGINE.

Application filed October 26, 1925. Serial No. 44,856.

My invention has for its object an internal explosion engine of the two cycle, double acting type, or of the two cycle single acting type, with the parts designed and arranged for minimum size and weight compared to the power output, without sacrificing the efficiency.

The engine of my invention is characterized by being free from stuffing boxes, and has full floating pistons mounted on a single piston rod with all of the joints between the explosion and compression compartments and the atmosphere made tight by the employment of piston rings.

My invention is especially designed to take care of expansion and contraction under the varying temperatures and conditions of operation and provides for the preheating of the air employed in the explosive mixture and special air cooling features for the piston head and surrounding parts and a special protection against the temperatures of explosion from reaching the piston rod.

The sliding joints between the piston and rings and the several cylinder walls are lubricated by oil introduced with the intake air or mixture.

The engine of my design is adapted either to the employment of explosive mixtures whether atomized into the cylinders or drawn in as a mixture of air and volatile hydrocarbon and is also adapted to ignition by any of the conventional devices as spark plugs, heated bulbs, or the like.

By referring to the accompanying drawing, wherein I have shown a characteristic two cycle double acting engine, my invention will be made clear.

In the drawing:

Fig. 1 is a longitudinal section of one form of engine employing my invention.

Fig. 2 is a fragmentary section on the line II-II of Fig. 1.

Throughout the figures similar numerals refer to identical parts.

A main base plate is indicated by the numeral 1, having machined receiving surfaces at 3, 4, 5 respectively and a slide surface at 6 on which the cross head 7 is adapted to reciprocate during the operation of the engine.

A connecting rod is shown at 8, from

which the power developed may be employed in any conventional manner.

A bearing is shown at 9 rigidly supported 55 on the machined surface 3 and in which the piston rod 10 is adapted to reciprocate.

At 11 and 12 are explosion cylinders water-jacketed at 13, 14 respectively.

Corresponding piston heads are shown at 60 15, 16 which may advantageously be provided with baffles 17, 18, and there are provided conventional explosion initiating means indicated by spark plugs 19, 20, cylinder inlet ports 21, 22 and discharge ports 65 23, 24 respectively.

The explosion cylinders 11, 12 are joined by the compression cylinder 25 as by conventional flanges and within this compression cylinder the piston head 26, 27 mounted 70 on the shoulder 28 of the rod 10, and abutting against the flange 29 is held in clamped relation thereto by the nut 70 and is adapted to reciprocate within the compression cylinder 25. 75

The piston heads 15, 16 are here shown integrally formed with the flange heads 26, 27 bolted together by the holding bolts 30 and the heads are formed with partitions 31, 32 whereby there are formed cooling 80 chambers 33, 34 respectively, in the heads 15, 16 and through which the in-flowing explosive mixture circulates to cool the heads 15, 16.

While passing through the chambers 33, 85 34, the said mixture is also preheated prior to its entry in the compression cylinder 25.

At 35, 36, 37, are shown outlet ports from the chambers 33, 34.

Referring particularly to Fig. 2, where 90 these ports are best shown, it will be noted that the ports 35, 36 register with ports 38, 39 in the cylinder walls respectively in one position during a reciprocating stroke of the rod 10. They are set off of the center so as 95 not to register with the port 21 during another portion of the rod stroke.

The inlet ports for the explosive mixture are shown respectively at 40, 41 and explosive mixture as from any conventional carburetor entering through ports 40, 41 circulates through the chambers 33, 34 cooling the heads 15, 16 respectively and preheating the mixture which then passes through ports 100.

35, 38 and 36, 39 into the compression cylinder 25, this description applying during the time that the parts are in the position shown in Figs. 1 and 2.

6 The compression space 43 in the cylinder 25 is thus filled with explosive mixture, which during the return stroke of the rod 10 in the direction of the arrow 44 is compressed, the ports 35, 36 at such time being 10 out of registry with the ports 38, 39, and the mixture is then forced by the movement of the head 26, 27 out of the port 45 and through the connecting pipe 46 at the time that the head 26 has moved to the left sufficiently to uncover the port 22, and scavenges 15 the cylinder 12 of the gases resulting from the previous explosion. These gases now pass out through the port 24 which is simultaneously uncovered by the head 16.

20 The next reciprocation stroke, when the rod 10 moves again to the right and into the full line position of Fig. 1, results in the compressing of the now contained explosive mixture in the cylinder 12, preparing it for 25 ignition, as by the spark plug 20.

When the explosion occurs, the rod is again driven in the direction of the arrow 44 to the left; and the cycle of operations is repeated.

30 At the time the parts are in the full line position of Fig. 1, assuming that cylinder 12 is now charged with compressed explosive mixture, ready to explode, or at the time of explosion, the cylinder 11 is being scavenged and charged with explosive mixture by previously compressed explosive mixture flowing from the compartment 47 through the pipe 48 and the port 21 into the cylinder 11 and the cylinder 11 now being charged 35 with explosive mixture, a compression takes place therein during the stroke of the rod 10 in the direction of the arrow 44 under the action of the expansion of exploded gases in cylinder 12.

40 It will thus be seen that while power is being developed through the movement to the left, in the direction of the arrow 44, by the piston head 16 under the action of the exploded gases in cylinder 12, an explosive 45 charge is being compressed in cylinder 11, and when the rod arrives at the end of the stroke the compressed mixture in the cylinder 11 is exploded and the rod again driven to the right.

50 In this way there is an explosion of compressed explosive mixture at each stroke of the rod in each direction, corresponding with two explosions, to-wit: one in each cylinder during a complete reciprocated cycle 55 of the rod 10, resulting in what is known as a two cycle, double acting, internal explosion engine.

It will be noted that metallic ring packing is employed throughout the movable parts, the piston head 15 being provided

with ring packing at 50 between the tubular member 52 and head 15 and at 51 between the wall of the cylinder 11 and the head 15, and in like manner the piston head 16 is provided with sealing rings at 54 between the piston 70 and tubular member 55 and at 56 between the piston 16 and the cylinder 12.

The compression cylinder 25 and piston head 26, 27 is sealed in like manner by the rings 57. In mounting the parts on the bed plate 1, it is to be noted that the pedestal bearing 9 is rigidly fixed thereto and that the cylinder 25 is preferably bolted solidly as on the plate joint 4 whereas the foot 60 of the cylinder member 11 and the foot 61 of 80 the cylinder member 12 are allowed a sufficient freedom of movement on the faces 3 and 5 to allow for expansion and contraction while having their weight fully supported and alignment maintained.

85 The piston is full floating on the sealing rings before mentioned and in the bearing 9 and slide 64.

Tubular members 52 and 55 extend respectively inward as a portion of the castings of cylinders 11 and 12 respectively and are made of an internal diameter in excess of the rod 10 allowing the air space at 62 and 63 respectively whereby air is freely drawn in and forced out during a cycle of 90 movements of the rod 10, thus cooling to an additional extent the cylinders 11 and 12 and insulating the rod 10 from the intense heat. A baffle 69 may be provided to prevent the heated air forced out through the passage 62 100 from overheating the bearing 9.

The size of the cylinder 25 is optional and may be made of such dimensions that the spaces 43, 47 correspond with a greater volume than the cylinders 11 and 12 respectively.

This is particularly advantageous where my invention is employed in engines of the Diesel type.

The engine shown in the drawings and above described, is of the two cycle double acting type and embodies a preferential form of my invention, but it will now be understood that by employing the cylinders 11 and 12 bolted together without the intermediate or third cylinder 25 and employing one of these cylinders as a compression cylinder and the other as an explosion cylinder my engine may be operated as a two cycle single acting engine while employing the 110 other features of my invention.

115 In such a construction the two cylinders, i. e. one right and the other left, form in fact a single cylinder member with the piston acting therein to compress the mixture 120 at one end and to receive the impulse of explosion from the other, and if preferred the two cylinders may be formed as a single casting in the conventional way with my invention embodied therein.

I have not shown any special means of oiling as I prefer to introduce the necessary lubricant for the various rubbing surfaces in minute quantities with the explosive mixture. This requires an extremely small quantity of oil which by this means is distributed throughout the entire running joint portions of the engine.

I claim:

1. In an internal explosion engine, a cylinder member closed at each end and a piston adapted to reciprocate therein, said piston having a cylindrical opening through a portion of its length and therebeyond fixed on a rod, said member having a bushing having a clearance space around said rod telescoping within said opening, a rod passing through the closed ends of the cylinder member and packing rings between said bushing and the walls of said cylindrical opening, ring packing between the piston and cylinder member, a bed plate on which said member is fixed and another portion of said bed plate on which another portion of said member contacts with a freedom of movement to allow for changes due to temperature variations.

2. In an internal explosion engine, a cylinder member closed at each end and a piston adapted to reciprocate therein, said piston having a cylindrical opening through a portion of its length and therebeyond fixed on a rod, said member having a bushing having a clearance space around said rod telescoping within said opening, a rod passing through the closed ends of the cylinder member and packing rings between said bushing and the walls of said cylindrical opening, said piston having a cooling passage and an inlet and an outlet port for said passage, and said cylinder member having corresponding ports with which said first named ports register at one position of its movement whereby a fluid is adapted to be admitted and discharged from said passage.

3. In an internal explosion engine a cylinder member closed at each end and a piston adapted to reciprocate therein, said piston having a cylindrical opening through a portion of its length and therebeyond fixed on a rod, said member having a bushing having a clearance space around said rod telescoping within said opening, a rod passing through the closed ends of the cylinder member and packing rings between said bushing and the walls of said cylindrical opening, said piston having a cooling passage and an inlet and an outlet port for said passage, and said cylinder member having corresponding ports with which said first named ports register at one position of its movement whereby a fluid is adapted to be admitted and discharged from said passage, ring packing between the piston and cylinder member, a bed plate on which said mem-

ber is fixed and another portion of said bed plate on which another portion of said member contacts with a freedom of movement to allow for changes due to temperature variations.

4. In an internal explosion engine, a cylinder member closed at each end and a piston adapted to reciprocate therein, said piston having a cylindrical opening through a portion of its length and therebeyond fixed on a rod, said member having a bushing having a clearance space around said rod telescoping within said opening, a rod passing through the closed ends of the cylinder member and packing rings between said bushing and the walls of said cylindrical opening, bearings external to said cylinder member supporting said rod and the clearance space between said bushing and said rod opening through said member to the atmosphere whereby air circulation is induced within said space when the piston and rod reciprocate.

5. In an internal explosion engine, a cylinder member closed at each end and a piston adapted to reciprocate therein, said piston having a cylindrical opening through a portion of its length and therebeyond fixed on a rod, said member having a bushing having a clearance space around said rod telescoping within said opening, a rod passing through the closed ends of the cylinder member and packing rings between said bushing and the walls of said cylindrical opening, bearings external to said cylinder member supporting said rod and the clearance space between said bushing and said rod opening through said member to the atmosphere whereby air circulation is induced within said space when the piston and rod reciprocate, said piston having a cooling passage and an inlet and an outlet port for said passage, and said cylinder member having corresponding ports with which said first named ports register at one position of its movement whereby a fluid is adapted to be admitted and discharged from said passage.

6. In an internal explosion engine a cylinder member closed at each end and a piston adapted to reciprocate therein, said piston having a cylindrical opening through a portion of its length and therebeyond fixed on a rod, said member having a bushing having a clearance space around said rod telescoping within said opening, a rod passing through the closed ends of the cylinder member and packing rings between said bushing and the walls of said cylindrical opening, said piston having a cooling passage and an inlet and an outlet port for said passage, and said cylinder member having corresponding ports with which said first named ports register at one position of its movement whereby a fluid is adapted to be admitted and discharged from said passage, ring packing between the piston and cylinder member, a bed plate on which said mem-

- inder member, a bed plate on which said member is fixed and another portion of said bed plate on which another portion of said member contacts with a freedom of movement to allow for changes due to temperature variations, bearings external to said cylinder member supporting said rod and the clearance space between said bushing and said rod opening through said member to the atmosphere whereby air circulation is induced within said space when the piston and rod reciprocate.
7. In an internal explosion engine a pair of cylinder members and therebetween a third cylinder adapted to receive and initially compress an explosive mixture a piston in each cylinder said three pistons rigidly fixed together and mounted on a rod, a cylindrical bored opening extending in each direction from said mounting and concentric and spaced from said rod, a bushing fixed with each of the end cylinders and spaced from and symmetrically positioned around said rod forming an air space therebetween, and telescoping with said cylindrical openings, a piston rod extending through all of said cylinders and externally supported, packing rings between each bushing and the corresponding cylindrical opening, bearings external to said cylinders supporting said rod, the space between said bushings and said rod opening through the cylinder ends to the atmosphere whereby air circulation is induced within said space when the pistons and rod reciprocate.
11. An internal explosion engine as set forth in claim 10 and a shield member between a cylinder and an adjacent bearing, adapted to divert the heated air expelled from said space.
12. An internal explosive engine comprising elements as set forth in claim 10 and a bed plate on which said third cylinder is fixed on which the other said cylinders are adapted to contact with a freedom of movement to allow for changes due to temperature variations.
13. An internal explosive engine comprising elements as set forth in claim 10, said pistons in said pair of cylinders each having a cooling passage therethrough with ports to and from said passage and corresponding ports in each of the pairs of cylinders with which said first named ports register in one position of said pistons at which time a cooling fluid is adapted to be admitted and discharged from said passages.
19. In an internal explosion engine a pair of cylinder members and therebetween a third cylinder adapted to receive and initially compress an explosive mixture a piston in each cylinder said three pistons rigidly fixed together and mounted on a rod, a cylindrical bored opening extending in each direction from said mounting and concentric and spaced from said rod, a bushing fixed with each of the end cylinders and spaced from and symmetrically positioned around said rod forming an air space therebetween, and telescoping with said cylindrical openings, a piston rod extending through all of said cylinders and externally supported, packing rings between each bushing and the corresponding cylindrical opening, bearings external to said cylinders supporting said rod, the space between said bushings and said rod opening through the cylinder ends to the atmosphere whereby air circulation is induced within said space when the pistons and rod reciprocate.
